WHEEL STRAIGHTENING APPARATUS

Frank M. Nimcheck, Morgantown, W. Va.

Application June 20, 1935, Serial No. 27,585

7 Claims. (Cl. 33—203)

This invention relates to an apparatus designed to straighten and true metallic wheels and their hubs or brake drum sections, particularly, but not necessarily of automobiles.

5 It is aimed to provide a novel apparatus wherein the object mentioned may be accomplished expeditiously and preferably through the use of a hand operable jack.

The more specific objects and advantages will 10 become apparent from a consideration of the description following taken in connection with accompanying drawings illustrating an operative embodiment.

In said drawings:—

15 Figure 1 is a view in elevation of the improved apparatus;

Figure 2 is an enlarged fragmentary substantially central vertical sectional view showing a wheel being straightened;

20 Figure 3 is a view substantially similar to Figure 2 but showing a hub and brake drum section being straightened;

Figure 4 is an enlarged elevation of the supporting section;

25 Figure 5 is an elevation of said supporting section taken at a right angle to Figure 4;

Figure 6 is a substantially central, enlarged vertical sectional view taken through the supporting section;

30 Figure 7 is a detail section taken on the line 7—7 of Figure 4;

Figure 8 is a plan view of the cap plate;

Figure 9 is an edge view partly broken away of said cap plate, and

35 Figure 10 is a plan view of the supplemental gauge plate.

In order to mount the various parts constituting the invention, a suitable framework such as that generally designated 10 is employed. Such 40 framework especially has an elevated or raised cross beam 11, and an upper open section 12, including a vertical sleeve 13 at the base of which a non-rising hand wheel 14 is swiveled. Such hand wheel 14 in effect is a nut since it has a 45 central screw-threaded opening in which a clamping screw rod 15 is screw-threaded for raising and lowering according to the direction of turning of the wheel or nut 14. As well as being operable by hand, the wheel 14 may be operated by power, 50 for instance, by a conventional lever arrangement 16 having a pawl 17 pivoted thereto at 18 and adapted to successively engage and push ratchet teeth 19 provided continuously about the wheel 14 in its upper surface.

55 The work to be straightened, for instance, a

wire-spoked or other metallic wheel 20, as used on automobiles, or the brake drum and hub section of that wheel as designated 21 is adapted to be supported on a cap plate 22, which extends partly into the work as shown, that is, either the 5 wheel 20 in Figure 2 or the section 21 in Figure 3. Such cap plate has a depending annular flange 23 whereby it is removably disposed at the top of a supporting pillar 24, the wheel 20 being clamped to the cap plate 22 by a plate 25 removably interposed between the wheel and clamp screw 15 as shown in Figure 2. In the case of the section 21, as in Figure 3, the same is removably clamped to the cap plate by a plate 26 usually somewhat smaller than the plate 25, and removably interposed between the section 21 and the clamping screw 15.

Said pillar 24 includes a lower open portion or cage 25 traversed at the lower end by a removable plate or bridge 26', for instance screwed in 20 place at 27. Cage portion 25 removably but snugly fits a recess 44 in bar 11 and a flange 45 on the cage rests on said bar 11. Slidable along the pillar is a gauge plate 28, the same having a hub 29 intimately fitting the pillar and engaged at 25 the lower edge by a pair of rods 30, slidably passing through openings 31 in the cage 25 and carried by a cross-head 32 to which they may be screwed as at 33, said crosshead 32 has the upper end of a screw shaft 34 removably journaled or 30 swiveled in the same as by a reduced portion 35 on the screw, and a nut 36 threaded into that reduced portion. Screw 34 is preferably operable by a hand wheel 37. The bridge piece 26, as best shown in Figure 7, is preferably of skeleton form 35 using cross bars or portions 38 for maximum strength.

Presuming a wheel 20 positioned as in Figures 1 and 2, for straightening, the straightening is 40 effected by the manual operation of a conventional jack 39, as shown in Figure 1, preferably disposed at a slight angle, in engagement with the frame portion 12 at the top, and the rim of the wheel at the bottom. This jack is of the type usually used for the raising of automobile 45 wheels. As one portion of the rim of the wheel 20 is straightened, the parts may be loosened and another portion brought into position for straightening. In order to gauge the wheel to see if it is true or straight, incidental to the use 50 of the jack, the gauge plate 28, is raised into contact with the relatively lower edge of the rim of the wheel in Figure 2, through the operation of the screw 34.

It will be noted that the gauge plate 28 has 55

a depression as at 40. Such depression is too large to engage the straightness or trueness of the relatively lower edge of the section 21, as in Figure 3, and in this connection, a supplemental gauge plate 41 is removably applied over the pillar 24 resting in a groove 42 of the gauge plate 28, with its upper surface flush with that of the gauge plate 28. The supplemental gauge plate 41 is preferably reinforced by ribs 43. In the testing or gauging of the section 21, the supplemental gauge plate 41 is raised, through the raising of the gauge plate 28, into contact with the relatively lower edge of the section 21. It will be realized that the jack is applied to any suitable gauge portion or portions of the section 21 as shown in Figure 3 in straightening the same.

Various changes may be resorted to provided they fall within the spirit and scope of the invention.

What is claimed is:—

1. Apparatus of the class described, comprising a pillar, a cap plate on said pillar to support an article to be straightened, means to clamp the article to the cap plate, and a gauge for the article movable along the pillar.

2. Apparatus of the class described, comprising a pillar, a cap plate on said pillar to support an article to be straightened, means to clamp the article to the cap plate, a gauge for the article movable along the pillar, said cap plate having a depending flange telescoped over the pillar, and means operable to raise and lower the gauge plate along the pillar.

3. Apparatus of the class described, comprising a pillar, a cap plate on said pillar to support an article to be straightened, means to clamp the article to the cap plate, a gauge for the article movable along the pillar, said pillar having a cage portion including a bridge, a screw operable in said bridge, a rod slidably in the cage portion engaging the lower portion of the gauge plate, and means operatively connecting the rod to the screw.

4. Apparatus of the class described, comprising a pillar, a cap plate on said pillar to support

an article to be straightened, means to clamp the article to the cap plate, a gauge for the article movable along the pillar, said gauge plate having a central depression in its upper portion to accommodate the work, and a supplemental gauge plate to accommodate smaller work than the first mentioned gauge plate, the supplemental gauge plate surrounding the pillar and being removably disposed in the depression.

5. Apparatus of the class described, comprising a pillar, a cap plate on said pillar to support an article to be straightened, means to clamp the article to the cap plate, a gauge for the article movable along the pillar, said gauge plate having a central depression in its upper portion to accommodate the work, a supplemental gauge plate to accommodate smaller work than the first mentioned gauge plate, the supplemental gauge plate surrounding the pillar and being removably disposed in the depression, the first mentioned gauge plate having a groove above said depression receiving the supplemental gauge plate with the upper surfaces of both gauge plates substantially flush.

6. Apparatus of the class described, comprising a pillar, a cap plate on said pillar to support an article to be straightened, means to clamp the article to the cap plate, a gauge for the article movable along the pillar, a frame mounting said pillar, said clamping means being a screw, a nut swiveled on the frame and in screw-threaded engagement with said screw operable to raise and lower the screw.

7. Apparatus of the class described, comprising a pillar, a cap plate on said pillar to support an article to be straightened, means to clamp the article to the cap plate, a gauge for the article movable along the pillar, a frame mounting said pillar, said clamping means being a screw, a nut swiveled on the frame and in screw-threaded engagement with said screw operable to raise and lower the screw, said frame having a recess, and said pillar having a cage disposed in said recess, and a flange about said cage resting on the frame about the recess.
